UNITED STATES PATENT OFFICE.

HENRY A. HANSEN, OF CHICAGO, ILLINOIS.

DESIGN FOR A COMBINATION LAMP AND PHONOGRAPH STAND.

Application filed January 28, 1924. Serial No. 8,466. Term of patent 14 years.

To all whom it may concern:

Be it known that I, HENRY A. HANSEN, a citizen of the United States, residing at Chicago, in the county of Cook and State of Illinois, have invented a new, original, and ornamental Design for a Combination Lamp and Phonograph Stand, of which the following is a specification, reference being had to the accompanying drawing, forming a part thereof.

The single figure of the drawing is an elevation showing my combination lamp and phonograph stand.

I claim:

The ornamental design for a combination lamp and phonograph stand as shown.

HENRY A. HANSEN.
